(57) **CLAIM**

The ornamental design for a dancing dolphins marble fountain, as shown as shown and described.

DESCRIPTION

FIG. 1 is a left side view of a dancing dolphins marble fountain showing my new design;

FIG. 2 is a right side view thereof;

FIG. 3 is a front elevational view thereof;

FIG. 4 is a top plan view thereof; and,

FIG. 5 is a rear perspective view.

The broken line showing is for illustrative purposes only and forms no part of the claimed design.
